(57) **CLAIM**

The ornamental design for a suitcase, as shown and described.

DESCRIPTION

FIG. 1 shows a perspective view of a suitcase design according to the invention.

FIG. 2 shows a front view of the design according to the invention.

FIG. 3 shows a rear view of the design according to the invention.

FIG. 4 shows a left side view of the design according to the invention.

FIG. 5 shows a right side view of the design according to the invention; and,

FIG. 6 shows a top side view of the design according to the invention.

As no bottom view is included in the drawings, the broken lines in FIGS. 1–5 indicate boundaries beyond which no claim is made.
